UNITED STATES PATENT OFFICE

91,454

DESIGN FOR A CASING FOR A PORTABLE ELECTRIC DRILL

Alonzo G. Decker, Towson, Md., assignor to The
Black & Decker Manufacturing Company,
Towson, Md., a corporation of Maryland

Application October 11, 1933. Serial No. 49,457

Term of patent 7 years

To all whom it may concern:

Be it known that I, ALONZO G. DECKER, a citizen of the United States of America, residing at Towson, Baltimore County, Maryland, have invented a new, original, and ornamental Design for a Casing for a Portable Electric Drill, of which the following is a specification, reference being had to the accompanying drawing, forming part thereof.

In the drawing:

Figure 1 is a side elevation of the drill casing showing my new design,

Figure 2 is a top plan view of the same, and
Figure 3 is a front elevation.

Referring to the drawing, the casing has a stream line effect, being of polygonal cross sec-

tion, having substantially flat longitudinal surfaces at the center and at the top and bottom, respectively, said surfaces being of greatest width near the center and of reducing taper toward the ends, and meeting in longitudinal edges which converge gradually toward the rear and more abruptly toward the front, terminating at the front adjacent the nose portion and at the rear adjacent the base of the spade handle, imparting a corresponding taper to the casing.

I claim:

The ornamental design for a casing for a portable electric drill as shown and described.

Signed by me at Towson, Baltimore County, Maryland, this 5th day of October, 1933.

ALONZO G. DECKER.
